UNITED STATES PATENT OFFICE.

WILLIAM H. BEVANS, OF BRIDGEPORT, CONNECTICUT, ASSIGNOR TO AMERICAN AND BRITISH MANUFACTURING COMPANY, OF NEW YORK, N. Y., A CORPORATION OF NEW YORK.

SEMI-AUTOMATIC BREECH-LOADING ORDNANCE.

SPECIFICATION forming part of Letters Patent No. 732,259, dated June 30, 1903.

Application filed November 18, 1902. Serial No. 131,796. (No model.)

To all whom it may concern:

Be it known that I, WILLIAM H. BEVANS, a citizen of the United States, residing at Bridgeport, in the county of Fairfield and State of Connecticut, have invented certain new and useful Improvements in Semi-Automatic Breech-Loading Ordnance; and I do hereby declare the following to be a full, clear, and exact description of the invention, such as will enable others skilled in the art to which it appertains to make and use the same.

This invention relates generally to improvements in breech-loading ordnance, and particularly to that class known as "semi-automatic," the object being to provide an improved construction to be applied to breech-loading guns for the purpose of utilizing the energy of the recoil of the gun, to cock the hammer, open the breech, extract the cartridge-case, and, when tripped automatically by the insertion of a fresh cartridge or by hand, to return the breech-block to its position closing the breech.

The special features of my invention are its simplicity and its adaptability with slight modifications to breech-loading ordnance having differently-constructed breech mechanism, it being not limited to guns provided with a breech-block movable transversely of the axis of the gun, as illustrated in the present instance, but may be used with other forms of breech mechanisms wherein the breech-block swings to open the breech or moves longitudinally.

Another important feature of the invention is that it may be applied to guns already in use, thus making the same semi-automatic.

In the accompanying drawings, Figure 1 is a side elevation of a portion of a gun provided with my invention, illustrating the normal position of the parts. Fig. 2 is a similar view showing the position of the parts when the gun has reached the limit of its recoil. Fig. 3 is also a side elevation showing the gun after its return to firing position, the mechanism having operated to cock the hammer and open the breech. Fig. 4 is an enlarged view of the inner cylinder or spring-casing. Fig. 5 is an enlarged sectional view through

one of the walls of the gun-breech and the 50 spring-cylinders, showing the shaft and crank for actuating the breech-block. Fig. 6 is a side elevation of the breech of the gun, partly in section, showing the exterior and the cam on the exterior of breech for automatically 55 disconnecting the spring-cylinders. Fig. 7 is a side elevation showing a hand tripping device for releasing the spring-cylinder to permit the same to move the breech-block to close the breech.

The gun here illustrated is provided with the common form of breech mechanism known as the "Hotchkiss" breech mechanism, some of the parts having been removed in the application of my invention, and said mechanism forms no part of my present invention. The Hotchkiss mechanism, briefly stated, consists of a drop-block A, which is adapted to be moved transversely of the axis of the gun B by a crank C on a shaft D, which projects to the exterior of the gun-breech. The end of the crank C moves in a cam-slot (not shown) in the block, so that when the shaft is rotated the block is moved to unmask the gun-bore or close the same. The extractor 3 75 (shown in dotted lines) is provided with a lug E', moving in an extractor-slot F, formed in the breech-block, (also shown in dotted lines.) As the block moves downwardly the extractor is drawn rearwardly, removing the empty cartridge-case from the gun, when the downward movement of the block is sufficient to unmask the bore. A crank-handle is provided for rotating shaft D, said handle carrying a 80 cocking-cam, which engages a cocking-toe G, (the latter being here illustrated in dotted lines,) and the first movement of said crank-handle effects the cocking of the hammer.

In the application of my invention to a gun provided with the breech mechanism above 90 set forth the crank-handle for shaft D and the cocking-cam operated thereby are removed, and upon said shaft on the exterior of the breech I mount two spring casings or cylinders H and I, between which is placed a 95 diaphragm J. The inner cylinder H is keyed to the shaft, while the outer one, I, is loose thereon. A post K is screwed into the ex-

terior of the breech of the gun and projects transversely through said cylinders, concentric slots L being formed in the walls of the latter, so that their rotation is not impeded by the post. Within cylinder H is a spring M and in cylinder I a spring N , said springs being secured at one end to the post K and at their opposite ends to their respective cylinders. These springs are so arranged as to wind oppositely—that is, while spring N is unwinding spring M is winding, and spring N is sufficiently stronger than spring M to wind the latter when it is itself unwinding. Thus while spring N is discharging its energy it is storing up energy in spring M . Cylinder or easing H is provided about a portion of its periphery with a flange or rim O , in the lower portion of which is formed an elongated slot O' . Cylinder I has on its periphery a casing P , carrying a spring-plunger P' , which rides upon said flange O of the inner cylinder and engages in said slot O' , so as to lock said cylinders together at the proper time for the purpose hereinafter set forth.

25 Loose upon shaft D is a short arm Q , to which one end of a rearwardly-extending arm or lever R is pivotally connected. The opposite end of said arm R is pivoted to an attaching-plate R' , secured to some convenient part of the mount A' . Arm Q has a toe Q' projecting on the opposite side of shaft D , and this toe engages a stud or lug I' on cylinder I .

30 The operation of the mechanism set forth is as follows: The parts being in the position illustrated in Fig. 1, the gun is fired and recoils longitudinally. The arm R being attached to the mount, and therefore fixed with relation to the gun, and having a pivotal connection with short-arm Q , which is loose in shaft D , causes said arm Q to rotate on said shaft as the gun moves rearwardly. The toe Q' of arm Q , abutting stud I' on cylinder I , which cylinder is also loose on shaft D , causes 35 said cylinder to rotate with arm Q , so that when the gun has reached the limit of its recoil spring-plunger P' , carried by cylinder I , has moved along flange O of cylinder H until slot O' has been reached, when said plunger has been forced therein by its spring. The parts are now in the position illustrated in Fig. 2. By this rotation of cylinder I the spring N therein has wound or energized. The gun having reached the limit of its recoil rapidly 40 returns to firing position, the toe on arm Q moving away from stud I' . The movement of arm Q is very rapid, owing to the rapidity with which the gun recoils and returns to firing position. The return movement of cylinder I by the unwinding of its spring is less rapid. The two cylinders being locked together by the spring-plunger, the inner cylinder H is also rotated with the outer one and is spring wound. The inner cylinder H being 45 fixed on shaft D , said shaft is also rotated, and through the medium of the engagement of crank C with the breech-block the latter

is moved downwardly to unmask the bore. When said block has nearly reached the limit of its downward movement, the toe S on plunger P' engages a cam-piece S' , secured to the breech, and as said cylinders continue their rotation the plunger is gradually forced from slot O' , so that when the block has reached the limit of its downward movement the plunger 75 entirely disengages said slot and the inner cylinder is released from the outer one. The spring in the inner cylinder has now been energized or wound, and as soon as said cylinder is released from the outer one said 80 spring starts to unwind and effect the return of the block to its position closing the breech of the gun. The extractor, however, in the meantime has been moved rearwardly by the breech-block and the empty cartridge-case 85 has been removed from the gun, and at the time the block begins to ascend a detent T , formed in the lug E of the extractor, is directly above a notch T' , cut in the extractor-slot of the block. The block therefore moves upwardly only a sufficient distance to cause said detent to engage the notch. Thus further rotation of the inner cylinder is prevented and the block locked in its downward position, so that a fresh cartridge may be placed in the gun. 90 The first movement of the inner cylinder as it is rotated by the outer cylinder cocks the hammer through the engagement of a cocking-cam U , formed on the outer wall of said inner cylinder with the cocking-toe G . As 95 will be understood, this cocking is effected before the block begins its downward movement. The parts have now assumed the positions shown in Fig. 3 and the gun is ready for loading. A cartridge is inserted and 100 pushed forward slightly to disengage the detent of the extractor-lug from the notch in the block. As soon as this is done spring M is free to unwind or discharge its energy, which it does, causing cylinder H and shaft 105 D to rotate, moving the block upwardly and closing the breech. Cylinder H is provided with a handle V for the purpose of operating the shaft D and opening the breech at the beginning of the firing, and also for the purpose of operating the breech-block by hand should any of the mechanism of the invention 110 become injured and not work effectively. Slot O' in cylinder H is of such length that plunger P' will always be in position to engage therein when the limit of recoil of the gun has been reached, even though the rearward movement of the gun in recoiling should vary. The end walls of the concentric slots in the spring-cylinder by engagement with the 115 spring-post limit the rotation of said cylinders and prevent the springs from entirely unwinding.

Referring now to Fig. 7, cam-piece S' is removed from the breech of the gun and in lieu thereof a bell-crank-tripping lever W is pivoted to the breech adjacent to the cylinders. To the long arm W' of this lever a cord or rope Y is attached, said rope being

carried to some convenient point on the breech and provided with a hand-grip Y'. A spring X connected with said lever serves to return the same to its normal position when it has been operated to release the inner cylinder from the outer one. The toe S of plunger P' engages the short arm W" of the bell-crank lever and the spring-cylinders are held from movement until said lever is operated to raise said plunger from the slot O' in the inner cylinder, when the breech-block is moved to close the breech, as in the first-described construction. In the construction illustrated in Fig. 7 it will be thus understood that the extactor does not hold the breech-block open, but this function is performed by the bell-crank lever, which also releases the inner cylinder from the outer one.

By providing a spring for moving the breech-block to open the breech the movement of the latter is effected without the shock and jar incident to constructions wherein the block is directly operated by the gun. In the present invention, while the gun recoils and returns to firing position with great rapidity, the unwinding of the spring is less rapid, and the block is thus gently and easily lowered without jar or shock.

Having thus fully described my invention, what I claim as new, and desire to secure by Letters Patent, is—

1. The combination with a breech-loading gun, a recoil-mount, and a breech-block, of means for storing the energy of the gun on its movement after a discharge, reacting between the gun and the block, for effecting the movement of the block to open the breech, and means for storing the energy of said breech-opening means for effecting the movement of the block to close the breech.

2. The combination with a breech-loading gun, a recoil-mount, a breech-block, and a breech mechanism for actuating the block to open and close the breech, of means storing the energy of the gun on its movement after a discharge, reacting between the gun and block for actuating said breech mechanism to open the breech, and means storing the energy of the breech-opening means for actuating said mechanism to close the breech.

3. The combination with a breech-loading gun, a recoil-mount, and a breech-block, of means for storing the energy of said gun on its movement after a discharge, reacting be-

tween the gun and block for moving the block to open the breech, and a spring energized by said breech-opening means for moving said block to close the breech.

4. The combination with a breech-loading gun, a recoil-mount, and a breech-block, of a spring storing the energy of the gun on its movement after a discharge, reacting between the gun and block for moving said block to open the breech, and means storing the energy of said spring for moving the block to close the breech.

5. The combination with a breech-loading gun, a recoil-mount, and a breech-block, of a spring energized by the movement of the gun after a discharge, reacting between the gun and block for moving the block to open the breech, and a spring energized by the breech-opening spring for moving said block to close the breech.

6. The combination with a breech-loading gun, a recoil-mount, and a breech-block, of a spring for actuating said block to close the breech, a spring for actuating the block to open the breech arranged to act reversely to the action of the breech-closing spring, means for placing said breech-opening spring under tension by the movement of the gun in recoiling, means for locking said springs together while said breech-opening spring is discharging its energy, and means for releasing said springs from each other to permit the breech-closing spring to close the block.

7. The combination with a breech-loading gun, a recoil-mount, and a breech-block, of a spring for actuating said block to close the breech, a spring for actuating said block to open the breech arranged to act reversely to the action of the breech-closing spring, an arm carried by a non-recoiling part of the mount, means for connecting said arm and breech-opening spring on recoil of the gun, means for locking said springs together while said breech-opening spring is discharging its energy, and means for releasing said springs from each other to permit the breech-closing spring to act to close the breech.

In testimony whereof I affix my signature in presence of two witnesses.

WILLIAM H. BEVANS.
